US0D1039276S

(12) United States Design Patent (10) Patent No.: US D1,039,276 S
(45) Date of Patent: * Aug. 20, 2024

(54) CARD CASE

(71) Applicant: Ao Zhang, Jingzhou (CN)

(72) Inventor: Ao Zhang, Jingzhou (CN)

() Term: 15 Years

(21) Appl. No.: 29/912,621

(22) Filed: Sep. 21, 2023

(51) LOC (14) Cl. 03-01

(52) U.S. Cl.

USPC D3/247

(58) Field of Classification Search
